UNITED STATES PATENT OFFICE

JAMES H. MARKS, OF DETROIT, MICHIGAN, ASSIGNOR TO PACKARD MOTOR CAR COMPANY, OF DETROIT, MICHIGAN, A CORPORATION OF MICHIGAN

DESIGN FOR A HORN BELL

Application filed December 29, 1931. Serial No. 42,280. Term of patent 14 years.

To all whom it may concern:

Be it known that I, JAMES H. MARKS, a citizen of the United States, residing at Detroit, county of Wayne, State of Michigan, have invented a new, original, and ornamental Design for Horn Bells, of which the following is a specification, reference being had to the accompanying drawings, forming a part thereof, and in which:

Fig. 1 is a perspective view of a horn bell incorporating my new design;

Fig. 2 is a front elevation thereof, and

Fig. 3 is a side elevation thereof.

I claim:

The ornamental design for a horn bell, as shown.

In testimony whereof I affix my signature.

JAMES H. MARKS.
